Primary Examiner — Karen E Eldridge Powers*Assistant Examiner* — Margaret Leah Bryan(74) Attorney, Agent, or Firm — Bayramoglu Law Offices LLC(57) CLAIM

The ornamental design for a lipstick container, as shown and described.

DESCRIPTION

FIG. 1 is a perspective view of a lipstick container showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict the embossments and other portions of the lipstick container in which the design is embodied that form no part of the claimed design.

1 Claim, 7 Drawing Sheets(56)
